SPACE HEATER SUPPORT

Donald W. Hartzell, Centralia, Ill., assignor to Lear Siegler Inc., Centralia, Ill., a corporation of Delaware
Filed Apr. 23, 1964, Ser. No. 361,976
9 Claims. (Cl. 126—85)

The present invention relates to apparatus for supporting a space heater adjacent to a window and for venting the heater and taking air into the heater through the window with a minimum of heat loss.

Heretofore, the installation of a space heater in a relatively permanent manner, ordinarily required the work of an expert. Installation was often complicated and required structural work in the room or building. Further, the apparatus for installing the heater tended to be complicated, costly and bulky. Prior efforts to alleviate these problems have not been particularly successful.

It is accordingly an object of the present invention to provide a novel and improved apparatus for the installation of a space heater. It is a more specific object to provide novel and improved installation apparatus for supporting a space heater adjacent to a window and for venting the heater and taking air into the heater through the window with a minimum of heat loss through the window.

Another object is to provide installation apparatus which permits rapid and easy installation of a heater in different size windows. It is a further object of this invention to provide installation apparatus of the type described which includes improved venting and air intake means for the heater. It is still another object of the invention to provide simple, economical and durable installation apparatus for securing a heater at a window.

Various other objects and advantages of the invention will become apparent from the following description and the drawings, wherein:

FIGURE 1 is a front perspective view of a space heater operably supported at the lower part of a double-sash, box-frame type window;

FIGURE 2 is an enlarged side sectional view, with parts broken away and in section, of the internal portion of a space heater such as shown in FIGURE 1, of installation apparatus for supporting the heater adjacent to the window and for venting the heater and taking air into the heater through the window, and of portions of the window construction, the installation apparatus embodying various features of the invention;

FIGURE 3 is a perspective view in reduced size of installation apparatus and window construction such as shown in FIGURE 2; and

FIGURE 4 is an enlarged exploded elevational view of the heater, the installation apparatus, and a portion of the window construction.

Briefly, the illustrated installation apparatus is adapted to support a space heater adjacent to a window and to vent the heater and take air into the heater through the window with a minimum of heat loss through the window. The installation can be done rapidly, simply and easily.

In the drawings, a space heater 10 is supported just inside a double-sash, box-frame type window 12 by installation apparatus 14. The heater 10 is vented out of the window and also receives a supply of fresh air through the window. The window is open to provide an opening to receive the installation apparatus 14, which includes an insulator plate 16 that is secured in the window opening and substantially covers the opening. The apparatus 14 also includes outlet or venting conduit means 18 and inlet or air intake conduit means 20 which are secured to and extend through the insulator plate 16.

Support means 22 attach to the frame of the window 12 and support the heater 10 in position on the inside of the window.

2

At the rear or side of the heater facing the window there is an outlet or outlet port 24 and an inlet or inlet port 26 disposed around the outlet. The conduits 18 and 20 are connected respectively to the outlet 24 and the inlet 26 of the heater, with the venting conduit 18 disposed inside the air intake conduit 20. To facilitate the connection of the internal venting conduit 18 to the outlet 26, the illustrated external inlet conduit 20 is retractable.

Thus, a simple yet highly effective construction of support, venting and air intake apparatus is provided for the heater.

The window 12 shown in the drawings includes a generally rectangular frame 30 disposed in a vertical wall 32. An upper window 34 is slideably received in vertical outer channels 36 at the sides of the frame 30, and a lower window 38 is similarly received in vertical inner channels 40 in the sides of the frame 30. The lower window 38 may be lifted or raised to a position such as shown in FIGURE 2. This creates the opening or space 42 wherein that portion of the installation apparatus 14 which vents and delivers fresh air to the heater is disposed. The frame 30 includes an inner sill or ledge 44 to which the means 22 that support the heater 10 are secured. The window sill 44 extends from side to side of the window 12 inwardly of the channels 40. It presents a generally rectangular elevated bar having a level upper surface and vertical inner and outer surfaces.

The support means 22 includes a generally rectangular vertical hanger plate 46 having an outwardly extending right-angle flange 48 disposed along its upper edge. The flange 48 rests upon the window sill 44 and adjustable spacers 50 on the lower portion of the hanger plate 46 may be extended or withdrawn to contact the vertical wall 32 and position the hanger plate 46 generally parallel to that wall in a substantially vertical alignment. The hanger plate 46 is secured to the sill 44 by a clamp bar 54. The illustrated clamp bar is a generally elongated horizontally disposed plate which is positioned over the flange 48 of the hanger plate 46. The bar 54 is provided with a right-angle lip or flange 56 along its outer edge which extends downwardly on the outside of the outer vertical surface of the window sill 44. The hanger plate 46 and the bar 54 are secured together by suitable means such as screws 58 with the plate 46 and the vertical flange 56 generally secured against the inner and outer vertical faces of the sill 44, as seen best in FIGURE 2, to firmly support the hanger plate 46 from the sill 44. The vertical edges of the illustrated hanging plate 46 are turned upon themselves in front of the plate to provide vertical slides or grooves 52, as shown best in FIGURE 4, for receiving and supporting the heater 10.

The illustrated insulator plate 16 is disposed in the space 42 created by the partially opened lower window 38, as seen best in FIGURE 2. The illustrated plate 16 is a generally rectangular vertically oriented plate made up of three sections which permit the plate to be extended and contracted to different widths. The illustrated plate 16 includes a center section 60 and a pair of end sections 62. The center section 60 has its upper and lower edges turned transversely to the plate and then toward the center of the plate to provide upper and lower grooves or races. Slideably received in the races from either side of the center section 60 are the end sections 62. The vertical side edges of each end section 62 are turned at right angles to the plate 16 to provide a securing flange 66 at either side of the insulator plate 16. The flanges 66 are secured in the lower portions of the inner channels 40 by suitable means such as screws 67 (FIGURE 4) to secure in place the insulator plate 16. The insulator plate thus extends across the width of the window 12 to cover the opening 42. In the illustrated structure, insulation such as molded rubber seal strips 68 are dis-

posed along the upper and lower edges of the insulator plate 16 to prevent the loss of heat around the edges of the plate. As shown in FIGURE 2, the lower window 38 is brought down to bear against the upper edge of the insulator plate 16 and the upper insulator strip 68 provides a thermoseal between the plate and the window.

The insulator plate 16 is provided with an aperture 70 for the venting and air intake conduits 18 and 20 as will be described below. More specifically, the center section 60 of the illustrated plate 16 is provided with a circular hole or opening and the inner vertical edge of each of the end sections 62 is provided with a semicircular cutout 61 so proportioned and aligned that if the end sections 62 are contracted, the semicircular cutouts and the circular hole are in general alignment so that the hole is not blocked. FIGURE 3 illustrates the extension of the end section 62 to the right, as viewed in that figure, to fit a particular window size.

Secured to the rear or outwardly disposed surface of the insulator plate 16 is a generally rectangular insulator box or box frame 77 that is generally centered around the aperture 70. The box or box frame 77 includes an upper, a lower, and two side walls which all extend rearwardly from the rear surface of the insulator plate 16 and are generally perpendicular to that rear surface. The edges of these walls are turned centrally inwardly to form a generally annular lip or flange 79 for the box frame 77.

Insulation may also be provided between the upper and lower windows, as by means of a square felt strip 72 as shown in FIGURE 2.

The heater 10 is supported in front of the window 12 as shown in the drawings. The inner or internal portion of the heater 74 is provided with vertical mounting angles 76, shown best in FIGURE 4, which are secured to the rear of the inner portion and are adapted to be received in the slides 52 of the hanging plate 46 to position and support the heater relative to the window. Suitable stop means, which may be adjustable if desired, but which are not specifically shown in the drawings, are used to secure the heater at the desired height. As seen best in FIGURE 2, the heater is positioned with outlet and inlet 24 and 26 in general alignment with the aperture 70 in the insulator plate 16. The outlet 24 through which the hot exhaust products of combustion emerge from the heater has a cylindrical collar 78 which extends rearwardly of the heater in the direction of the window and the insulator plate 16. The inlet 26 for taking cooler fresh air into the heater is disposed around the outlet 24 and is provided with a similar cylindrical collar 80. The inlet collar 80 is generally concentrically disposed around the collar 78, and extends outwardly from the rear of the heater inner portion 74 a somewhat shorter distance than does collar 78.

As best shown in FIGURE 4, the vent or outlet conduit 18, which is disposed within the intake conduit 20, is comprised, in the illustrated structure, by a pair of telescoped pipe sections having generally circular cross sections. The smaller pipe section is designated 82 and the larger pipe section is designated 84. Thus, the outlet conduit 18 may be extended or contracted lengthwise by moving the sections relative to one another. At the outwardly disposed end 86 of the vent conduit 18, which is provided by the outwardly disposed end of the larger pipe section 84, the vent conduit is secured to a vent cap assembly 88.

The illustrated vent cap assembly 88 is comprised of four generally vertical rectangular plates or baffles 90, 91, 92 and 93 which are secured together in parallel spaced-apart relation and in general alignment. The innermost baffle plate 93, which is the baffle plate to which the vent conduit 18 is secured, is provided with a circular center hole or aperture 96 that has an inwardly directed annular flange 98. The outer end 86 of the conduit 18 fits over and is secured to the flange 98. Marginal portions 99 of the baffles 90, 91, 92 and 93 are offset to

provide a more indirect discharge of the hot gases and material from the heater and to more effectively block incoming drafts. The two intermediate baffles 91 and 92 are generally similar to baffle 93, but are provided with somewhat larger center apertures 100 and 101 (FIGURE 2). The end or outermost baffle 90 is similar to the others but it does not have an aperture. The other or inward end 102 of the vent conduit 18, that is provided by the inward end of the smaller pipe section 82, is disposed around the outlet collar 78 of the heater. Thus, the hot gases and exhaust material from the heater pass through the outlet 24 of the heater, through the pipe sections 82 and 84 comprising the vent conduit 18 of the installation apparatus 14, and are diffused and diverted, particularly by the end baffle 90, to pass indirectly into the surrounding air. The vent cap assembly 88 retards undesired flow of cool outside air back through the vent conduit 18 toward or even into the heater.

The air intake conduit 20 is disposed around the vent or outlet conduit 18 and is comprised, in the illustrated structure, of a pair of telescoped pipe sections having a generally circular cross section. The larger pipe section is designated 104 and the smaller one is designated 106. The two sections are movable relative to one another to extend or contact the length of the intake conduit 20.

The inner end 107 of the air intake conduit 20, or more particularly the inner end of the smaller pipe section 106, is connected to the collar 80 of the heater inner portion 74, and thereby communicates with the intake 26 of the heater. The outer end 108 of the air intake conduit 20, or more particularly the outer end of the larger pipe section 104, is connected to an inlet assembly 110. The inlet assembly 110 which, like the air intake conduit 20, is disposed around the vent conduit 18, includes generally a cylindrical intake grating 112 having a transverse rectangular annular flange plate 114 and 118 at either end. The outer end 108 of the conduit 20 is connected to the inner end of the intake grating 112. The plate 114, which is outermost or furthest from the heater, is disposed just inwardly of the innermost baffle 93 of the vent cap assembly 88 and is secured to that assembly by means of bolts 94 (FIGURE 2). The plate 118, which is innermost or closest to the heater, is of approximately the dimensions of the square box frame 77 and is secured to the frame along the annular flange 79 so as to provide an outer or rear wall for the box or box frame 77. Thus, fresh air from outside enters the intake grating 112, passes through the pipes 104 and 106 that comprise the intake conduit 20, and enters the heater through the inlet 26.

The connection of the plate 118 to the frame 77 also fixes the position, in a direction normal or perpendicular to the window wall 32, of the conduits 18 and 20, the vent cap assembly 88, and the air intake assembly 110, except for the telescoped smaller pipe sections 82 and 106. The telescoped pipe sections 82 and 106 remain longitudinally movable toward or away from the heater to provide the appropriate connection with the intake and outlet collars 78 and 80 of the heater. The enclosure defined by the box or box frame 77 and the plate 118 thus provides a ring of air or insulating medium around the conduits 18 and 20 adjacent their outside or outer junction with the insulator plate 16.

After suitable connections are made from the heater to a source of gas (not shown), the outside cabinet 122 is placed upon the heater inner portion 74 as shown in FIGURE 1 and the heater is ready for operation.

As noted above, the operation of the heater is quite simple insofar as the venting and induction of material is concerned. The hot material and gases pass out of the outlet 24 of the heater, through the vent conduit 18 and out between the baffles 90, 91, 92 and 93 of the vent cap assembly 88. The cool outside air is at the same time drawn in through the grating 112, and passed through the

intake conduit 20. This incoming air in the intake conduit 20 thus moves through the area surrounding heated outlet conduit 18 to the intake 26 of the heater and is heated, whereby more effective and efficient operation of the heater 10 is provided.

The adjustable length of the conduits 18 and 20, and particularly the intake conduit 20, are of decided advantage in effectively securing the heater and the apparatus in location in the window. It permits the assembly made up of the conduits 18 and 20 and the insulator plate 16 to be secured in desired location, i.e., seated in the window frame channels 40, to provide desirable insulation characteristics and the like, despite variations in window dimensions. Specifically, except for the movable portions of the conduits 18 and 20 the assembly of parts are fixed against movement in a direction transverse to the plane of the window wall 32. The heater 10 is also fixed against movement in this direction and positioned by the location of the front edge of the window sill 44 which determines the location of the hanger plate 46 upon which the heater is supported. However, the distance between the inside edge of the window sill 44 and the location of the channels 40 may differ from window to window. Using conduits of adjustable length permits ready installation of the heater together with the desired fixed installation of the bulk of the assembly in the manner described above. In this connection, it would not generally be desirable to make the entire conduits movable relative to the plate since it is generally preferred to have the conduits fixed and relatively sealed to adjacent parts where the conduit and these adjacent parts are exposed to the outside to minimize leakage and heat loss.

Further, it provides for convenient fabrication to have the larger, externally disposed inlet conduit 20 retractable so that it may be moved out of the way while the smaller internally disposed vent conduit 18 is connected to the heater. Then the external inlet conduit 20 may merely be extended and itself connected to the heater.

Thus, the illustrated installation apparatus 14 provides simple, practical and effective means for supporting a space heater adjacent a window and using the window to vent the heater and also to take in air for the heater, all with a minimum of heat leakage or loss. The illustrated structure also provides for particularly advantageous structural features which permit ready and efficient installation of a space heater in different windows of a variety of different dimensions.

Various changes and modifications may be made in the illustrated structure without departing from the spirit and scope of the invention. Various features of the invention are set forth in the following claims.

What is claimed is:

1. Installation apparatus for supporting, at a window in an exterior wall of an area to be heated, a space heater having an outlet and an inlet for venting the heater and providing air to the heater through the opening provided by the window being open, said apparatus comprising:

(a) insulator means adapted to be secured to the wall adjacent to the window opening so as to substantially close the opening,

(b) support means adapted to be secured to the wall adjacent to the window and adapted to support the space heater with the outlet and inlet of the heater adjacent to said insulator means, and

(c) inlet conduit means and outlet conduit means secured to and extending through said insulator means and adapted to connect, respectively, to the inlet and outlet of the heater to provide two-way communication between the heater and the opposite side of said insulator means.

2. Installation apparatus for supporting, at a window of an exterior wall of an area to be heated, a space heater that has an outlet and an inlet and for venting the heater and providing air to the heater through the

opening provided by the window being open, said apparatus comprising:

- (a) an insulator plate adapted to be secured to the wall adjacent to the window opening so as to substantially cover the opening,
- (b) an elongated inlet conduit and an elongated outlet conduit secured to and extending through said insulator plate to provide two-way communication between opposite sides of said plate, said outlet conduit being disposed within said inlet conduit, and
- (c) support means adapted to be secured to the wall within the area and adjacent to the window opening, said support means being adapted to support the space heater with the outlet and inlet of the heater positioned for connection, respectively, with the ends of the outlet and inlet conduits disposed within the area.

3. Installation apparatus for supporting, at a window of a room wall, a space heater that has an outlet and an inlet and for venting the heater and providing air to the heater through the opening provided by the window being open, said apparatus comprising:

- (a) an insulator plate adapted to be secured to the wall adjacent to the window opening so as to substantially cover the opening,
- (b) an elongated inlet conduit and an elongated outlet conduit secured to and extending generally horizontally through said insulator plate to provide two-way communication between the points spaced substantially from either side of said plate, said outlet conduit being disposed within said inlet conduit, and
- (c) support means adapted to be secured to the wall within the room and adjacent to the window opening, said support means being adapted to support the space heater with the outlet and inlet of the heater in generally direct alignment, respectively, with the ends of the outlet and inlet conduits disposed within the room.

4. Installation apparatus for supporting, at a window of a room wall, a space heater that has its inlet for cooler air disposed around its outlet for warmer exhaust gases, the heater being supported adjacent to the window which is of the generally rectangular box-frame double-sash type wherein two windows are movably supported in vertical side channels of a window frame, one window being open to provide an opening to accommodate venting and an intake means for the heater, said installation apparatus comprising:

- (a) a generally rectangular insulator plate adapted to be secured at one end of the channels of the open window so as to substantially cover the opening defined by the frame and that open window,
- (b) support means adapted to be secured to the window frame and to the heater to support the space heater with its outlet and inlet adjacent to said insulator plate,
- (c) an inlet conduit and an outlet conduit secured to and extending through said insulator plate to provide two-way communication between the two sides of said plate, said outlet conduit being disposed within said inlet conduit, said outlet and inlet conduits adapted respectively to connect to the outlet and inlet of the heater,

whereby relatively hot exhaust gases from the heater are vented outside the room and air coming into the heater is pre-warmed and an effective seal is provided to prevent unnecessary dissipation of heat from the interior of the room.

5. Installation apparatus for supporting, at a window of an exterior wall of a room, a space heater that has its inlet for receiving cooler outdoor air disposed around its outlet for warmer exhaust gases, the heater being supported adjacent to the window which is of the box-frame double-sash type wherein two windows are movably sup-

ported in vertical side channels of the window frame, the lower window being open to provide an opening to accommodate venting and intake means for the heater, said installation apparatus comprising:

- (a) an insulator plate adapted to be secured at the lower portion of the channels for the open lower window so as to substantially cover the opening defined by the frame and that open lower window,
  - (b) an elongated inlet conduit and an elongated outlet conduit secured to and extending through said insulator plate to provide two-way communication between the two sides of said plate, said outlet conduit being disposed within said inlet conduit, each of said conduits having one of its ends spaced substantially inwardly and one of its ends spaced substantially outwardly of said insulator plate,
  - (c) support means adapted to be secured to the window frame and to the heater to support the space heater with its outlet and inlet in general alignment respectively with the inwardly spaced ends of the outlet and inlet conduits, said outlet and inlet conduits adapted to be operatively connected, respectively, to said outlet and inlet of the heater,
- whereby relatively hot exhaust gases from the heater are vented to the outdoors and cooler air from the outdoors coming into the heater is pre-warmed and an effective seal is provided to prevent unnecessary dissipation of heat from the interior of the room.

6. Adjustable installation apparatus for supporting a space heater at a window in an exterior wall of an area to be heated, the window being open to provide an opening to accommodate means that provide communication between the heater and the region outside of the wall, said installation apparatus comprising:

- (a) an insulator plate adapted to be secured in fixed relation to the wall so as to substantially cover the window opening,
- (b) support means adapted to be secured in fixed relation to the wall and to the heater to support the space heater in the area to be heated and adjacent to said insulator plate,
- (c) an adjustable conduit secured to and extending through said insulator plate to provide communication between the heater and the opposite side of said insulator plate, said conduit comprising a first elongated pipe section secured to said plate and having one end disposed inwardly of said plate and one end disposed outwardly of said plate, said conduit also comprising a second elongated pipe section that is in telescoped engagement with the inwardly disposed end of said first pipe section for longitudinal movement relative to said first pipe section, said second pipe section being adapted to connect to said heater.

7. Installation apparatus for mounting a space heater adjacent to a window that is located in an exterior wall of the area to be heated, and for venting the heater and taking in air for the heater through the opening provided by the window being open, said heater having an inlet port and an outlet port, one port being smaller in section disposed within the other, said apparatus comprising:

- (a) means adapted to support the heater adjacent to the window opening,
- (b) an insulator plate adapted to be secured to the wall so as to substantially cover the window opening, and
- (c) a pair of elongated conduits secured to and extending through said plate, one conduit being smaller in section than the other and being disposed within the other, the ends of said conduits in the area to be heated being adapted for connection to one of the ports of the heater, both of said conduits being fixed to said plate against longitudinal movement

but the larger conduit being longitudinally retractable and extendable to permit ready connection of first the smaller conduit to the smaller port of the heater and then the larger conduit to the larger port of the heater.

8. Installation apparatus for supporting, at a window in an exterior wall of an area to be heated, a space heater that has a first port that is larger in section and is disposed around a second port, the window being open to provide an opening to accommodate means that connect the ports of the heater to the region outside of the wall, said installation apparatus comprising:

- (a) an insulator plate adapted to be secured to the wall so as to substantially cover the window opening,
- (b) support means adapted to be secured to the wall and to the heater to support the space heater in the area to be heated and with its first and second ports facing said insulator plate,
- (c) an elongated inlet conduit and an elongated outlet conduit secured to and extending through said insulator plate to provide two-way communication between the two sides of said plate, one of said conduits being larger and being disposed around the other of said conduits, the larger of said conduits comprising a first elongated pipe section that is secured to said plate and has its ends disposed respectively inwardly and outwardly of said insulator plate, said larger conduit also comprising a second elongated pipe section that is in telescoped engagement with the inwardly disposed end of said first pipe section for longitudinal movement relative to said first pipe section, said outlet and inlet conduits each adapted to be operatively connected to one of said ports of the heater.

9. Installation apparatus for supporting, at a window in an exterior wall of an area to be heated, a space heater having an outlet and an inlet for venting the heater and providing air to the heater through the opening provided by the window being open, said apparatus comprising:

- (a) insulator means adapted to be secured to the wall adjacent to the window opening so as to substantially close the opening,
- (b) support means adapted to be secured to the wall adjacent to the window and adapted to support the space heater with the outlet and inlet of the heater adjacent to said insulator means, said support means comprising a vertical hanger plate with a flange along its upper edge, said flange being adapted to rest upon the window sill, a clamp bar having a flange adapted to be positioned against the outer vertical surface of the window sill, fastening means for securing said clamp bar to said hanger plate, and
- (c) inlet conduit means and outlet conduit means secured to and extending through said insulator means and adapted to connect, respectively, to the inlet and outlet of the heater to provide two-way communication between the heater and the opposite side of said insulator means.
